UNITED STATES PATENT OFFICE.

JOHN SETECKA, OF CHICAGO, ILLINOIS, ASSIGNOR TO JAMES TETEAK, OF CHICAGO, ILLINOIS.

WATER-HEATER.

1,241,154.

Specification of Letters Patent. Patented Sept. 25, 1917.

Application filed February 23, 1915. Serial No. 10,065.

To all whom it may concern:

Be it known that I, JOHN SETECKA, a citizen of the United States, residing at Chicago, in the county of Cook and State of Illinois, have invented certain new and useful Improvements in Water-Heaters, of which the following is a description.

My invention belongs to that general class of devices known as water heaters, and relates particularly to a heater arranged for attachment to a stove, and particularly that type of stove burning gas, oil, or the like. The device is particularly adapted to be employed upon any of the well known styles of stoves now on the market without materially changing or rebuilding the stove except for removing the usual detachable rack or frame arranged over the burners for supporting cooking utensils or vessels, and substituting my combined heating attachment and utensil support in its place. The invention has among its objects the production of a device of the kind described that is simple, convenient, durable, efficient and satisfactory. It is extremely efficient in its operation and almost instantly heats the water to a high temperature, and with gas or the like that is utilized at the same time for heating or cooking purposes. While the flame is utilized to heat the water, the same is done without any appreciable effect on the cooking. By employing my improved heater, where more than one heater is provided upon the stove, one heater may be utilized as a warmer upon which cooked articles may be placed and kept warm until desired for use. Many other objects and advantages will appear from the construction shown and described to those familiar with such devices or skilled in the art.

To this end my invention consists in the novel construction, arrangement or combination of parts herein shown and described, and more particularly pointed out in the claims.

In the drawings, wherein like reference characters indicate like or corresponding parts,

Figure 1 is a top plan view of a portion of a gas stove, with my heater applied thereto;

Fig. 2 is a sectional view of the same taken substantially on line 2, 2 of Fig. 1;

Fig. 3 is a sectional view of the type of baffle shown at the right in Fig. 1;

Fig. 4 is a sectional view taken substantially on line 4, 4 of Fig. 2;

Fig. 5 is a sectional view through one of the heaters, showing a slightly different form of baffle;

Fig. 6 is a top elevation of a portion of a heater having supports adapted to be broken or fractured to fit the device to a particular size stove;

Fig. 7 is a sectional view taken substantially on line 7, 7 of Fig. 6;

Fig. 8 is a similar view of an adjustable form of support, and

Fig. 9 is a top plan view of the same.

Referring to the drawings, in which the preferred form of my device is shown, 1 represents the top frame of any suitable form or style of stove, particularly a gas stove, and 2, 2 two of the burners. Ordinarily an additional burner 3 is employed in connection with one of the burners 2, as shown in Fig. 2. I have shown only a portion of the top of the stove, it being understood that there may be any desired number of burners, and that the burners may be of any suitable style, those shown for illustration being in the form of a tubular annular ring having slots formed in the same for the escape and burning of the gas. The style of heater herein shown is suitable for any of the burners now on the market, and therefore the type of burners shown are only for illustration. The gas is supplied to the stove through the usual supply pipe 4, the control of the same to any of the burners being made through the usual valves 4. I have not considered it necessary to illustrate all of the valves, nor the detailed construction of the same, as they may vary to some extent in different stoves without having any bearing on the present invention.

My preferred form of heater consists of a tubular annular member 5, provided with the desired number of supports 6, preferably extending radially. These radial supports are formed of sufficient length to engage with the frame 1 of the stove, and they may be constructed as hereinafter set forth so as to be easily adjusted or made to fit various sizes of stove tops. The heater (see Fig. 4) is provided with an inlet and outlet 7 and 8, either one of which may be considered as the inlet, and the other as the outlet. The ring may also be formed with inwardly and radially extending projections

9, which are preferably chambered, as shown. The projections or extensions 9 serve to support small cooking utensils or pans over the burner, and increase the heating surface, and being chambered, do not overheat or burn off. I have shown several plugs 10 arranged about the heating ring. These are to close up the openings formed in casting the ring, as the same is preferably cast, and therefore necessarily cored. Water may be admitted to the heater through either one of the pipes shown, as for example, pipe 11, and conducted therefrom through pipe 12. In Figs. 1 and 2 is shown a battery of two heaters, pipe 12 being connected to the other heater, which is provided with a discharge pipe 14, which may be likewise connected to other heaters, or to a supply tank. In this connection I might mention that I have not considered it necessary to illustrate a supply or storage tank, as this may or may not be employed, depending upon the individual preference and the requirements of the users.

At the left hand burner shown in Figs. 1 and 2, I have shown a baffle 15, which may be cast integrally with the supports 6. At the right hand side I have shown a baffle 16, preferably formed of pressed sheet metal, and arranged at 17 to slip over the supports, the outer edge being flanged downwardly and preferably at an angle, as most clearly shown in Fig. 3. The baffle gathers all heat that passes out the other side of the heating ring 5. While the baffles are not altogether necessary, particularly where only one burner is employed, the same is desirable when the additional burner 3 is provided as a part of the stove. The form shown in Fig. 3 is also very desirable where the heater is employed for warming purposes, as will be hereinafter referred to.

As shown in Fig. 5, in which 18 represents the heater, the baffle 19 is further extended as at 20, so as to gather in practically all of the heat, so that none is lost. In Fig. 6, 21 represents the tubular annular member and 22 radially extending supporting arms. In this form I have shown the same formed with grooves, as at 23 (see Fig. 7) so that where the top of the stove is slightly smaller than the heater the radially extending arms may be fractured very easily, or otherwise removed. Figs. 8 and 9 illustrate a tubular annular member 24, formed with fixed arms 25, to which are secured adjustable extending parts 26, the parts being secured together by screws 27 carried by one part, and extending through a slot in the other. To avoid confusion I have not shown either the construction shown in Figs. 6 and 7 or 8 and 9 in Figs. 1 and 2. These constructions are, of course, not necessary, as the arms may be sawed off to fit with a hack saw or the like, or filed down, but they afford a simple and convenient way for the house-

holder in fitting the device to any ordinary stove, particularly where it is not a standard size.

In use, assuming that several heaters are employed on the stove, whenever the burner is lighted the water in the tubular annular members is heated, and if a storage tank is employed the water circulates in the usual manner. The heater, however, is instantaneous in action, and only in rare cases is a storage tank required. When several of the devices are employed, as for example as shown in Fig. 1, if the burner at the left is lighted, hot water will circulate through the heater at the right regardless of whether the burner is lighted or not. Articles to be kept warm may be placed upon the heater to the right without danger of burning or boiling over. If desired, a pan 28, or other receptacle, may be turned over the heater, covering any article carried thereby, and completely containing the heat. I have mentioned a pan, as ordinarily in most cases, this would serve the purpose, but a specially constructed cover, formed with heat insulated walls might be employed. In that case the heater would form substantially a fireless cooker.

The form of baffle shown in Fig. 3, and at the right of Figs. 1 and 2, is particularly convenient, and is preferred, as it may be made in several sizes and is easily detachable in cleaning the heater and burner. The distance between the heater and the burners may, of course, be made as desired, and ordinarily they are some closer than shown in the drawings.

While the device is particularly intended for use in homes such as houses and small apartment buildings, it is as equally desirable for use in restaurants and hotels, barber shops, and the like. While the heat strikes the heater on its way to the cooking utensil, flat iron, or the like, some heat is likewise deflected back against the heater, thereby again utilizing what would otherwise be lost.

Having thus described my invention, it is obvious that various immaterial modifications may be made in the same without departing from the spirit of my invention; hence I do not wish to be understood as limiting myself to the exact form, construction, arrangement, or combination of parts herein shown and described, or uses mentioned.

What I claim as new and desire to secure by Letters Patent is:—

1. A water heating attachment for gas stoves, comprising a tubular annular member, having an inlet and an outlet at the under side thereof, means for supporting said member from the top of the stove, consisting of a plurality of arms extending radially from the exterior, for engagement

5 with said stove top, said member provided with a plurality of inwardly extending tubular vessel supporting arms, and a sheet metal baffle member formed to overlie the radially extending supporting arms to be supported thereby, and bent down at an angle between the arms with a space between the baffle and outer and upper sides of the annular member.

10 2. A water heating attachment for gas stoves, comprising a tubular annular member, having an inlet and outlet at the underside thereof, adjustable means for supporting said member from the top of the stove, consisting of a plurality of arms extending radially from the exterior of the member, and having extending parts adjustably se-

cured thereto, and formed for engagement with said stove top, said member provided with a plurality of inwardly extending tubular vessel supporting arms, and a detachable baffle member consisting of a sheet metal plate formed to overlie said radially extending supporting arms, and bent down between the arms at an inclination, and 25 spaced from the annular member at the outer and upper sides of the same.

In testimony whereof, I have hereunto signed my name in the presence of two subscribing witnesses.

JOHN SETECKA.
